UNITED STATES PATENT OFFICE.

WILLIAM DALTON, OF GLENVILLE, NEW YORK.

RAILROAD-TRACK STRUCTURE.

Application filed February 1, 1927. Serial No. 165,136.

This application is a continuation in part of my application Serial No. 136,448, filed Sept. 20, 1926.

The invention relates to railroad track structures and especially to railroad track structures wherein the ties are formed from metal.

One object of the invention is to provide an improved form and construction of rail fastening means well adapted for use with a tie which may be formed with advantage from structural shapes, such as H-beams or lengths of old or worn rail, fastened together by means of angle irons and standard tie plates, the rail fastening means comprising members which are simple in structure and capable of being obtained readily at low cost in either small or large quantities.

20 A further object of the invention is to provide an improved rail fastening means which is easily and quickly positioned without the use of special tools and which when positioned is held firmly in place so it cannot rattle or jar loose whereby it forms a safe and secure fastening means for the rail.

For a consideration of what I believe to be novel and my invention, attention is directed to the following description and the 30 claims appended thereto.

In the drawing, Fig. 1 is a perspective view of tie structures with which my improved fastener may be used; Fig. 2 is a sectional view taken on line 2-2, Fig. 3; Fig. 3 is a perspective view, partly in section, of one end of a tie having a rail fastened thereon by fastening means embodying my invention; Fig. 4 illustrates the manner in which the fastening means may be put into place; Fig. 5 is an enlarged sectional view showing the rail fastening means in position; Fig. 6 is a side elevation of a modified form of fastener; and Fig. 7 shows a short length of track having rails attached by rail-fastening means embodying the invention.

Referring to the drawing, the track tie comprises two lengths of tie bars 1 and 2 which stand in spaced relation to each other and are fastened together at their ends by angle bars 3 and 4. One wall of each angle bar is located beneath the base flanges of the tie bars and the other wall extends transversely across the ends of the tie bars. The 55 bottom flanges of the tie bars and the wall of the angle bar which is located beneath

them are welded together as is indicated at a. The wall extending across the ends of the tie bars may be or may not be welded to the tie bars as is found desirable. Ordinarily, when tie bars such as worn rails are made into lengths they are first nicked and then broken. This leaves the ends rough and irregular in shape, and often the lengths are not exactly equal in length. As a result, it may be difficult to weld to the ends of them. However, by using angle bars as shown, which extend beneath and are welded to the bottom flanges of the tie bars, I avoid any difficulties as far as the irregular 60 ends are concerned because the bottom surface of the base flanges of the tie bars are smooth and flat and welding at this point gives a strong enough bond between the parts. The vertical walls of the angle bars 65 70 75 80 85 90 95 100 105 110 115 120 125 130 135 140 145 150 155 160 165 170 175 180 185 190 195 200 205 210 215 220 225 230 235 240 245 250 255 260 265 270 face of the tie plate. Upper inturned end 16 extends at an angle to portion 14 such that it will project over the top of the rail base flange 20. As will be seen, the rail clamping member is simple in structure and may be made by being bent from rolled stock, by being forged from suitable material, or by being made from cast steel.

Fastener 13 comprises a spring key of a size suitable to fit in the openings in the tie plate behind the clamping members 12. The two prongs or arms 21 of the spring key are spaced apart normally as is indicated in Fig. 4 and the key is formed from comparatively heavy spring steel which means that considerable force is required to move the two prongs toward each other and that when moved toward each other there then exists a force of considerable magnitude tending to separate the prongs or arms. The space behind rail clamping members 12 is of a width less than the normal width of the spring key so that when the key is forced into the space, the key is compressed whereby it serves to hold clamping member 12 firmly in position. At the same time, it is itself also held firmly in position.

In the use of a spring key as above described, one of the problems is that of getting it into position in the slot behind the rail fastener. This is because of the inherent rigidity of the arms of the key. Ordinarily, track rails are laid by relatively unskilled labor, and it is desirable, therefore, to avoid the use of special tools or any operations requiring special skill. I have overcome this difficulty by providing the ends of prongs or arms 21 with outer and inner bevel surfaces 22 and 23, the bevels being sufficient so that the overall width of the lower end of the key is such that when the outer lower corner of one prong 21 is placed against the upper edge of slot 11 as shown in Fig. 4, the bevel surfaces 22 being in engagement with the edge of the slot, then bevel surface 23 engages the outer surface of fastener 12. At this time the spring key is located at an angle as shown in Fig. 4. Now, when the spring key is struck on the end with a hammer or other suitable instrument it is forced down into opening 11 behind fastener 12 as illustrated in Fig. 5. By this arrangement, the key may be put in position by the use of an ordinary hammer. When in position inherent springiness of the key serves to hold the key in place. The upper end of the key is provided with a relatively large eye which is useful in removing the key. To remove the key the sharpened end of a bar may be inserted into the eye and used as a pry to lift the key. Or, a pin may be inserted through the eye to provide a projection and the key then pried out by means of a bar placed under the projecting end of the pin.

In Fig. 6 I have shown a modified form of

spring key. It is similar to the spring key shown in Figs. 4 and 5, differing from it only in that bevel surfaces 25 and 26 corresponding to the bevel surfaces 22 and 23 of Figs. 4 and 5 are formed by inturned ends 70 or extensions 27 at the free ends of the arms 28 of the key.

My improved rail fastener possesses a number of advantages which are very important from a practical commercial stand- 75

The U-shaped fasteners and the steel spring keys can be obtained at low cost in either large or small quantities. This is because the U-shaped fastener is of simple section which means that it can be easily rolled or forged; and the spring keys may be made by bending plate stock of suitable width and thickness to desired shape and then cutting it into suitable lengths to form the keys. As a result, the fasteners and keys can be provided at a cost comparable to that of the track spikes required for similar service.

The fasteners and key are quickly and easily positioned and may be easily and readily removed. This is a thing of primary importance.

When positioned, the fastening means is held firmly in place and will remain tight in service, it being not possible for it to loosen as is the case with ordinary spikes. Tests have demonstrated that the fastening means is at least ten times as effective as are regular track spikes.

Also, it will be noted that plate 8 is a standard tie plate so it is readily obtainable in the open market. The rib 9 on the tie plate serves to hold the rails from spreading, which takes considerable load off the rail fastening means. As a result, a lighter weight fastening means may be used than would be the case were the ribs not present.

In combination with my improved rail fastening means and for cooperation here-with, I provide an anti-creeping arrangement for both the rails and the ties. To this end, I make the angle bars at the ends of the rails of a length such that they abut against each other, as indicated in 29, and I then provide at suitable points on the rail flanges projections 30 which stand at opposite sides of the end 16 of a rail fastener. Projections 30 may be built up by fusing metal to the rail flange, using a welding machine for the purpose, or they may be formed on the rail when it is rolled. Projections 30 need be provided only at spaced points, it being unnecessary to provide them at every tie. With this arrangement, creeping of the rail is prevented by projections 30 engaging ends 16 of the rail fasteners. And the abutting angle bars at the ends of the rails serve to distribute the stress among the several ties, so that the stress is not borne by the single tie appurtenant to the 130

projections 30. Since the successive ties abut one another at their ends, each individual tie is held from displacement by the adjacent ties.

5 While I now prefer to provide projections 30 on base flange 20 in positions such that they cooperate with fastener ends 12, my invention is not limited thereto but projections may be similarly provided engaging 10 other fixed abutments. Certain features disclosed are not claimed herein as they form subject matter of my application Serial No. 220,811, filed September 20, 1927.

In accordance with the provisions of the 15 patent statutes, I have described the principle of operation of my invention, together with the apparatus which I now consider to represent the best embodiment of my invention, but I desire to have it understood that 20 the apparatus shown is only illustrative and that the invention may be carried out by other means.

What I claim as new and desire to secure by Letters Patent of the United States, is:—

25 1. The combination with a tie including a plate having an opening therein, of a rail on said plate, a U-shaped fastener in said opening, one end of which engages beneath said plate and the other over the top of the 30 base flange of the rail, and a flat spring key in the opening behind said fastener, the

arms of said spring key extending transversely of the tie and being normally spread apart a distance greater than the width of the space behind the fastener whereby when 35 the spring key is inserted in the opening behind the fastener the arms are forced toward each other and are maintained in such position to permanently hold the fastener in place. 40

2. The combination with a tie including a plate having an opening therein, of a rail on said plate, a U-shaped fastener in said opening, one end of which engages beneath 45 said plate and the other over the top of the base flange of the rail, and a flat spring key in the opening behind said fastener, the arms of said spring key being normally spread apart a distance greater than the width of the space behind said fastener 50 whereby when the spring key is inserted in the opening behind the fastener the arms are forced toward each other and are maintained in such position to permanently hold the fastener in place, the ends of said arms 55 being beveled so that the key may be inserted by placing it at an angle and driving it into position.

In witness whereof, I have hereunto set my hand this 31 day of January, 1927.

WILLIAM DALTON.
